CLAIM

The ornamental design for a welding consumable container, as shown and described.

DESCRIPTION

FIG. 1 is a top, front perspective view of a welding consumable container;

FIG. 2 is a top, rear perspective view thereof;

FIG. 3 is a bottom, rear perspective view thereof;

FIG. 4 is a front elevation view thereof;

FIG. 5 is a rear elevation view thereof;

FIG. 6 is a right side elevation view thereof;

FIG. 7 is a left side elevation view thereof;

FIG. 8 is a top plan view thereof; and,

FIG. 9 is a bottom view thereof.

The broken lines show portions of a welding consumable container which form no part of the claimed design.

1 Claim, 7 Drawing Sheets
